UNITED STATES PATENT OFFICE.

RUSSELL H. BOWEN, OF PALMYRA, NEW JERSEY, ASSIGNOR TO THE AMERICAN PULLEY COMPANY, OF PHILADELPHIA, PENNSYLVANIA, A CORPORATION OF PENNSYLVANIA.

PULLEY.

1,027,639.

Specification of Letters Patent.

Patented May 28, 1912.

Application filed July 19, 1910. Serial No. 572,680.

To all whom it may concern:

Be it known that I, RUSSELL H. BOWEN, of Palmyra, county of Burlington, and State of New Jersey, have invented new and useful Improvements in Pulleys, whereof the following is a specification, reference being had to the accompanying drawings.

My invention relates to that class of pulleys in which insets of cork, or other material having a relatively high coefficient of friction, are employed, and the object of my invention is to simplify the construction of such pulleys, and at the same time to insure proper support for the insets against inward pressure, in a radial direction, and to hold them against lateral displacement.

In the drawings, Figure I, represents a side elevation of a pulley embodying my invention; Fig. II, being an axial section 20 thereof on the line II, II, of Fig. I.

The pulley comprises a hub portion 1, to which are attached a plurality of spoke-pairs 2, 2, converging symmetrically toward the median plane of the pulley as shown in 25 the sectional view.

The rim of the pulley is formed of an integral piece of sheet metal, folded back, or returned upon itself, as shown in Fig. II, so as to constitute an outer rim 3, and 30 an inner rim 4, with an interspace 5, of substantial radial depth between them. The edges of the metallic sheet which forms the inner rim, are bent abruptly into flanges 6, and 7, which extend radially inward adjacent to the median plane of the pulley 35 structure, and are received between the outer ends of the spoke-pairs 2, 2, and are there secured by means of rivets 8.

At suitable intervals in the outer rim 3, 40 I form a plurality of holes 10, of a proper size to receive the insets 12, of cork or other material, which are of slightly larger diameter than the holes, so that when forced into position, the material can expand in the interspace 5, beneath the edges of the holes 10, and thus insure a firm grip.

I am aware that it is not new to provide a pulley with insets inserted in a separate band of metal secured upon the external 50 face of the rim by means of rivets, screws, or other fastening devices. By my invention however, the continuity of the inner and outer rims attained by folding the sheet metal back upon itself, affords not only great

structural strength with a given weight of 55 metal, but is highly economical to manufacture, and affords the proper conditions for maintaining the insets in position against displacement. I also am aware that it is not broadly new to construct the rim of a pulley 60 of two thicknesses of metal lying in close contact with one another. The characteristic of a pulley embodying my invention is that a substantial and definite interspace is left between the outer and inner rims for 65 the purposes and with the results above set forth.

In the drawings and foregoing description I have specified what is commercially termed a "whole pulley", as distinguished 70 from a divided pulley, made in two similar half parts, secured together at the rim and at the hub.

My invention is of course adapted for use 75 in connection with such divided pulleys, and it will, therefore, be understood that in applying the term integral to the rim, I do not mean that the entire circumference must necessarily be made in one piece, but that the metal of the outer rim is integral with 80 that of the inner rim, throughout either the whole pulley, or each part thereof.

Having thus described my invention, I claim:

The combination of a hub; a plurality of 85 spokes mounted thereon; a rim of sheet metal folded back upon itself to form an outer rim and an inner rim integral therewith, but separated therefrom by an interspace of substantial radial depth, the edges 90 of the metal of said inner rim being provided with flanges extending radially inward adjacent to the median plane of the pulley, said flanges being attached to the outer ends of the spoke members; the outer 95 rim being provided with a plurality of holes; and insets of material having a relatively high coefficient of friction, arranged within said holes, the inner ends of the insets resting upon the surface of the inner 100 rim, substantially as set forth.

In testimony whereof, I have hereunto signed my name, at Philadelphia, Pennsylvania, this fifteenth day of July 1910.

RUSSELL H. BOWEN.
